PICKER FOR SPINNER FRAMES

Andrew B. Shelton, Columbus, Ga.

Application February 12, 1945, Serial No. 577,432

7 Claims. (Cl. 57—56)

This invention relates to spinning frames, and more particularly to an improved picker for removing lint accumulating adjacent the spindle.

An object of this invention is to provide a picker for lint which can be easily and quickly coupled to the spindle, the picker including an elongated flexible shaft so that the needle may be engaged with adjacent parts of the spinning frame for picking up lint or other fibrous material.

Another object of this invention is to provide a picker of this kind which is coupled directly to a spindle and operated thereby.

A further object of this invention is to provide a picker of this kind which includes an improved normally released clutch so that the picking needle may be optionally operated and can be quickly cleaned without decoupling the device from the spindle.

With the above, and such other objects in view as may hereinafter more fully appear, the invention consists of the novel construction, combination and arrangement of parts as will be more specifically referred to and illustrated in the accompanying drawing, wherein are shown embodiments of the invention, but it is to be understood that changes, variations, and modifications may be resorted to which fall within the scope of the invention, as claimed.

With the above and such other objects in view as may hereinafter more fully appear, I have invented the device shown in the accompanying drawing, in which:

Figure 1 is a fragmentary side elevation, partly in section, of a spinning frame having mounted thereon a picker constructed according to an embodiment of this invention.

Figure 2 is a fragmentary longitudinal section of the inner end of the device.

Figure 3 is a fragmentary longitudinal section of the outer or needle end of the device.

Figure 4 is a sectional view taken on the line 4—4 of Figure 3.

Figure 5 is a sectional view taken on the line 5—5 of Figure 1.

Referring to the drawing the numeral 10 designates generally a spinning frame, which has rotatably mounted thereon a plurality of spindles 11, carried by a rail 12 and rotated by means of a flexible belt 13. The spinning frame 10 also includes a long draft system of rollers, generally designated as 14, and thread or yarn guide members 15 are hingedly secured as at 16 to a supporting bar or rail 17. There is a thread guide 15 for each spindle 11, and these guides may be

swung upwardly as shown in Figure 1, to an inoperative position.

During the winding of the yarn or thread on the bobbin or other element engaging the spindle 11, a considerable amount of lint drops from the yarn and unless this lint is periodically removed it frequently is picked up by the yarn as the latter is being wound on the bobbin and forms slubs in the yarn.

10 In order to provide an improved means whereby this lint may be easily and quickly picked up while the spinning frame is in operation, I have provided a needle 18 which, as shown in Figure 4, is triangular in transverse section. The needle 18 includes a rounded shank 19, which is journaled in a pair of bearings 20 and 21 carried by the opposite legs 22 and 23 respectively of a U-shaped support 24. The U-shaped support 24 is formed integral with or secured to an elongated resilient arm or strap 25, which is provided with a reverted portion 26 secured by fastening members 27 to a hollow handle 28. The round shank 19 has secured thereto a roller 29 and this roller is normally disposed in spaced relation to a driving roller 30 secured to a rotatable shaft 31. The shaft 31 is journaled in anti-friction bearings 32 and 33 disposed in a bore 34 formed in a bearing member 35. The shaft 31 is formed with a polygonal opening 36 at its inner end within which the polygonal end 37 of a flexible shaft 38 is adapted to removably engage.

The shaft 38 is rotatably disposed in a flexible sheath 39 which is extended through an opening 40 formed in the inner end of the handle 28 and the sheath 39 is also extended into an opening 41 formed in the bearing 35. A set screw 42 is threaded through bearing 35 and engages sheath 39 so that it will hold the sheath in the bearing 35 and retain the shaft 38 in the recess or opening 36.

40 A bored plug 43 is threaded into the outer end of the bearing 35 and provides a means for retaining a lubricant in the bore 34.

The shaft 38 and the sheath 39 are of substantial length and have secured to the opposite ends thereof a housing 44. The housing 44 is of cylindrical construction and has rotatably mounted therein a shaft 45. The shaft 45 is journaled through a pair of anti-friction bearings 46 and 47 disposed in the housing 34, and the shaft 45 is formed with a polygonal socket or recess 48 within which the polygonal inner end 49 of the shaft 38 removably engages.

55 A sleeve 50 is secured to the sheath 39, and is formed with a flanged lower end 51 adapted to

engage against the inner end of the housing 44. An apertured or flanged cap 52 is threaded on the upper end of the housing 44, and bears against the flanged lower end 51 of the sleeve 50, so as to tightly hold the sheath 39 with respect to the housing 44.

The shaft 45 has secured thereto below the housing 44, a knurled wheel 53 by means of which the shaft 45 may be grasped in one hand so as to hold the shaft against rotation while a chuck 54 which is threaded on the lower end of shaft 45 is adjusted to either clamp or release the chuck from the spindle 11.

In order to provide for holding the housing 44 against rotation when the chuck 54 is engaged with a spindle 11, I have provided a laterally projecting arm 55 which is secured as at 56 to the housing 44. The arm 55 is adapted to engage against one side of a thread guide 15, which is in operative position so as to thereby hold housing 44 against rotation.

In the use and operation of this device the chuck 54 is clamped to spindle 11, one of the thread or yarn guides 15 being swung upwardly to permit the housing 44 to engage between a pair of adjacent thread guides associated with adjacent spindles. A handle or housing 28 is grasped in one hand, the hand engaging about the needle carrier arm 25. Arm 25 may be swung inwardly toward handle or housing 28 thereby bringing roller 29 into engagement with driving roller 30. Needle 18 will thereupon rotate and this needle may be projected about the desired parts of the spinning frame so as to wind loose yarn thereabout. When it is desired to clean the needle, roller carrying arm 25 may be released so that rocker 29 will be disengaged from roller 30. The needle 18, being of tapered construction, will permit ready removal of the lint toward the small end thereof.

I claim:

1. A picker for connection with and operation by a spindle of a spinning frame comprising a flexible shaft, a picking needle at one end of said shaft and a chuck secured to the opposite end of said shaft and adapted to grip said spindle for rotation and sole support thereby.

2. A picker for connection with and operation by a spindle of a spinning frame, comprising a flexible shaft, a housing at one end of said shaft, a normally inactive picking needle carried by said housing, normally inoperative clutch means carried partly by said needle and partly by said shaft whereby said needle may be selectively rotated, and means carried by the other end of said shaft for coupling the latter to said spindle for rotation thereby.

3. A picker for connection with and operation by a spindle of a spinning frame comprising a flexible shaft, a housing about said shaft at one end thereof, a picking needle, means rotatably supporting said needle from said housing laterally of said shaft, releasable coupling means for coupling said needle with said shaft for rotation by the latter, a second housing about said shaft adjacent the opposite end thereof, a chuck connected to the opposite end of said shaft engageable with said spindle, and means carried by said second housing engageable with a stationary part of said spinning frame for holding said second housing against rotation.

4. A picker as set forth in claim 3 wherein said releasable coupling means includes a wheel secured to said shaft, and a second wheel secured to said needle.

5. A picker as set forth in claim 3 wherein said supporting means comprises bearing means for said needle, and a resilient support for said bearing means carried by said first housing.

6. A picker as set forth in claim 3, wherein said supporting means comprises a resilient member fixed relative to said first housing, a U-shaped element carried by a free end of said resilient member, bearings for said needle carried by the opposite arms of said U-shaped member, a wheel secured to said needle between said bearings, and a second wheel secured to said shaft, said first wheel being normally disengaged from said second wheel.

7. A picker, as set forth in claim 3, wherein said latter means comprises a laterally projecting arm carried by said second housing.

ANDREW B. SHELTON.
